LIQUID SHAMPOO DISPENSER

Robert E. Watson, Farmington, Mich., assignor to Swedish Crucible Steel Company, Detroit, Mich., a corporation of Michigan

Filed Sept. 30, 1966, Ser. No. 4,112

Term of patent 14 years

(Cl. D4—3)

FIG. 1

FIG. 2

FIG. 3

The rear of the liquid shampoo dispenser is substantially flat and plain.

I claim:

The ornamental design for a liquid shampoo dispenser, as shown and described.
